Primary Examiner—Alan P. Douglas*Assistant Examiner*—R. Spear*Attorney, Agent, or Firm*—Michael H. Minns[57] **CLAIM**

The ornamental design for a seal engaging ring, as shown and described.

DESCRIPTION

FIG. 1 is a top plan view of a seal engaging ring showing my new design;

FIG. 2 is a bottom plan view of FIG. 1;

FIG. 3 is a side elevational view of FIG. 1 all other side elevational views being identical thereto;

FIG. 4 is a perspective view of FIG. 2; and,

FIG. 5 is a cross-sectional view taken on line 5—5 of FIG. 2.

The broken line showing of a retaining ring is for illustrative purposes only and forms no part of the claimed design.

FIG. 1

FIG. 2

FIG. 3

FIG. 4

FIG. 5
